UNITED STATES PATENT OFFICE

139,064

DESIGN FOR A PHOTOELECTRIC SUPERVISOR

John A. Long, Cambridge, Mass.

Application March 15, 1944, Serial No. 112,907

Term of patent 7 years

(Cl. D61—1)

To all whom it may concern:

Be it known that I, John A. Long, a citizen of the United States of America, residing at Cambridge, in the county of Middlesex and Commonwealth of Massachusetts, have invented a new, original, and ornamental Design for a Photoelectric Supervisor, of which the following is a specification, reference being had to the accompanying drawing, forming a part thereof.

Fig. 1 is a perspective view of the photoelectric supervisor, and

Fig. 2 is a side elevation illustrated in another position, showing my new design.

I claim:

The ornamental design for a photoelectric supervisor, substantially as shown.

JOHN A. LONG.
